UNITED STATES PATENT OFFICE.

JAMES M. EIFFE, OF FULTONVILLE, NEW YORK, ASSIGNOR TO THE WHITE MOP WRINGER COMPANY, OF NEW YORK, N. Y., A CORPORATION OF NEW YORK.

COMBINED MOP WRINGER AND PAIL.

Application filed February 2, 1926. Serial No. 85,424.

My invention relates to mop wringers shown in the accompanying drawings and more particularly described in the following specification and claims.

5 This invention relates to the type of mop wringer in which the wringer mechanism and pail are combined as a unitary device; the wringer mechanism consisting of a pair of rollers, one of which is journaled in stationary bearings attached to the wall of the pail, the other roller being journaled in a pair of swinging arms actuated by a foot-treadle whereby the rollers may be closed together over a mop, preliminary to pulling 10 the latter between the rollers to express the water therefrom.

One of the features of the present invention consists in mounting the pail upon a pair of skid-rails adapted to project beyond the 20 wall of the pail at one end—the projecting ends of the rails being connected together to form a handle which in conjunction with a swinging bail provides means whereby the pail may be readily tipped to discharge water contained therein.

Another feature of the invention consists in providing the forward end wall of the pail with a relatively wide-spout spaced from the roller when the latter is in its initial position, in order that any lint, dirt or other solid matter which may have entered the pail with the water expressed from the mop, will flow freely under the roller and out by the way of the spout when discharging the 30 contents of the pail—the construction being such that the roller will not arrest the passage of the lint or other solids contained in the pail and thereby dam up the water when discharging the latter therefrom.

40 Another feature of the invention consists in providing a vertically disposed strap bent to hook over the upper edge of the pail and riveted to its side wall above the water-level therein—that it may not rust and leak around the rivet—the lower end of the strap being bent beneath the pail to engage the bottom of the latter with a return bend extending beyond the end wall to receive the operator's foot that the pail may be held 45 against slippage when pulling the mop through the rollers to express the water therefrom.

Another feature of the invention consists in providing the supporting rails and foot-

piece with projecting skid points whereby 55 the device may be readily skidded or shifted over the floor.

With the foregoing and other objects in view which will appear as the description proceeds the invention further resides in the combination and arrangement of parts and in the details of construction hereinafter described and claimed it being understood that changes may be made in the precise embodiment of the invention herein disclosed without departing from the spirit of the same.

In the drawings accompanying this specification and forming a part thereof:

Figure 1 is a perspective view of the combined mop wringer and pail as viewed from its spout end, showing the rollers in their released or expanded position.

Figure 2 is a perspective view seen from the opposite end of the pail.

Figure 3 is a side elevation with parts broken away and in section, showing in dotted lines the swinging roller and its controlling foot-lever in the position occupied when engaging a mop, preliminary to expressing the water therefrom.

Referring now to the letters of reference placed upon the drawings:

A indicates a pail of rectangular formation provided with a spout A^a at its forward end, mounted upon a pair of skid-rails B—B secured to the bottom of the pail adjacent its side walls. The skid-rails project backwardly from the spout end of the pail beyond its rear wall where they are connected together by a cross-member B¹, which serves as a 50 handle for tipping the pail, or as a foot-rest to hold it when withdrawing the mop from between the rolls, as required.

C is a roller journaled in fixed bearings carried by the side walls of the pail near its 55 rear end.

D is a roller journaled in a U-shaped strap E secured to a swinging yoke F pivoted at G to the skid-rails B—B.

A pair of rocking levers H—H, are also 100 pivoted at G and are connected by tie-bars I with the swinging arms F.

The free ends of the levers H—H are joined together by a foot-treadle J; which when operated forces the swinging arms F 105 with the roller D toward the roller C, to grip the mop inserted between the rolls.

K is a spring, one end of which projects

through an aperture in the lever F, the other end being engaged to one of the skid-rails B, to return the swinging lever F and the roller carried thereby back to its initial position when the foot-lever is released from manual control.

L—L are straps secured to the side and end walls of the pail to stiffen the structure.

10 M is a bail fitted with a suitable handle M¹ to facilitate carrying the pail and in discharging its contents.

N is a vertical strap and foot-piece secured to the end wall of the pail. The upper end of the strap N is provided with a hook N¹ which overlaps the upper edge of the pail. The lower end of the strap is bent beneath the pail with a return bend N² extending in front of the pail to receive 20 the foot of the operator, preliminary to drawing the mop through the rollers to express the water from the mop; the pail being thus held against movement and without danger of upsetting or suddenly shifting, 25 which might cause the contents to be spilled.

Suitable raised lugs or points P may be formed on the lower flange of the skid-rail, and like projections N³ may be struck up 30 on the foot-piece of the strap N to serve as skids whereby the pail may be readily moved over the floor without the necessity of lifting or carrying it.

When it is desired to discharge the contents of the pail, the attendant lifts the pail 35 by means of the bail M in one hand, and with the other grasps the bar B¹ connecting the skid-rails. The pail may then be tipped readily in a forward direction so that its contents will flow below the swinging roller 40 and over the spout at the end of the pail.

A material advantage in providing the forward end of the pail with a spout is that any lint, chips or other dirt which may have 45 entered the pail will flow freely under the roller and over the spout and will not be dammed by the roller adjacent the end wall

of the pail as common in mop wringers of this type of construction.

So also by providing the forward end of the device with a foot-piece and strap hooked over its upper edge, it is relieved of considerable strain upon its working parts when withdrawing the mop while under the gripping pressure of the rollers applied to express the water therefrom. 55

Having thus described my invention what I claim is:

1. In a mop wringer, a tank, having one of its end walls bulged outwardly from side to side at its top edge, said bulged portion tapering inwardly and downwardly to form a relatively wide spout, a substantially U-shaped member having its sides embracing the sides of the tank and its bight portion lying normally over the upper edges of the tank at one edge immediately in advance of the mouth of said spout, means whereby to swingingly mount said U-shaped member, the sides of which latter constitutes swing- 60 ing arms, a mop wringing mechanism mounted within the tank and having connection with said U-shaped member, and means for actuating the mop wringing mechanism, the spout permitting lint, chips or other foreign matter which may have 65 entered the pail to flow freely from under the bight portion of said U-shaped member and from under the mop wringing mechanism upon tilting the tank. 70

2. In a mop wringer, a tank, a mop wring- 80 ing mechanism mounted within the tank, means for actuating the mop wringing mech- anism, and a vertically disposed strap se- 85 cured to the tank and including a hook en- gaging over the upper edge of the tank, the lower end of the strap being bent upon itself to project beneath the bottom edge of the tank and having a projecting step portion extending outwardly away from the tank. 90

In testimony whereof, I sign this specification.

JAMES M. EIFFE.
